UNITED STATES PATENT OFFICE.

LOUIS ALTERSON, OF AVERNE, NEW YORK.

DESIGN FOR A BUCKLE.

56,246.

Specification for Design.

Patented Sept. 7, 1920.

Application filed June 29, 1920. Serial No. 392,893. Term of patent 14 years.

To all whom it may concern:

Be it known that I, LOUIS ALTERSON, a subject of the King of Roumania, residing at Averne, county of Queens, State of New York, have invented a new, original, and ornamental Design for Buckles, of which the following is a specification, reference being had to the accompanying drawing, forming part hereof, in which—

Figure 1 is a perspective view of a buckle in its closed position, showing my new design, and

Fig. 2 is a perspective view of the same in open position.

I claim:

The ornamental design for a buckle as shown.

LOUIS ALTERSON.
